PRESS WITH PLATE TYPE FRAME

Walter Ernst, Mount Gilead, Ohio, assignor to
The Hydraulic Development Corp. Inc., Wil-
mington, Del., a corporation of Delaware

Original application April 8, 1938, Serial No.
200,964. Divided and this application January
5, 1939, Serial No. 249,483

1 Claim. (Cl. 100—19)

This invention relates to presses, and in particular, to frame constructions for presses.

One object of this invention is to provide a press having a frame wherein the head, bed and side members engage one another by means of a plurality of projections or lugs.

Another object is to provide a press wherein the head and bed are provided with projections or lugs passing through apertures in plate-like side members so that the thrust of the press is transferred to the side members in straight lines longitudinally along the side members, and substantially without transverse thrust components.

Another object is to provide a press having a head and bed which are provided with lugs seated in correspondingly shaped apertures in plate-like side members forming the strain elements interconnecting the head and bed, so that the working thrusts are transferred to the plate-like side members in substantially rectilinear directions without oblique or transverse thrust components.

This is a division of my copending application, Ser. No. 200,964, filed April 8, 1938.

In the drawing:

Figure 1 is a front elevation of a press having a frame construction according to one embodiment of the invention.

Figure 2 is a right-hand side elevation of the press shown in Figure 1.

Figure 3 is a horizontal section along the line 3—3 in Figure 2.

Figure 4 is a horizontal section along the line 4—4 in Figure 1.

In general, the press of this invention includes a head and a bed having projecting lugs engaging correspondingly shaped apertures in the side members. These side members are in the form of heavy steel plates, and receive the thrusts created by the action of the platen of the press. In the present invention these lugs pass entirely through the side plates and thereby transmit the thrusts in longitudinal straight lines to the side members. In this manner oblique thrusts or outward components are eliminated, so that there is no tendency for the side members to bend outwardly or become distorted during the operation of the press. Where the lugs on the head or bed pass only partially through the side plates and not entirely through them, an eccentric condition exists as to the lines of stress so that the end portions of the side plates tend to be pulled outwardly. In the present construction, however, where the lugs pass entirely through the side plates, the result is a straight pull on the

side plates and therefore there is no tendency to distort them.

Referring to the drawing in detail, Figures 1 and 2 show one embodiment of this invention, employing an upwardly-acting plunger. The press of Figure 1 consists of a bed 10 and a head 11 having lugs or projections 12 and 13, respectively. These lugs engage apertures 14 and 15, respectively, near the lower and upper ends of the frame side members 16. The stresses are transmitted through these connections between the lugs 12 and 13 and the apertures 14 and 15, the parts being nominally held together by the cap screws 17. The latter, however, are not depended upon to transmit thrust but merely serve as connecting members to hold the parts in assembly. In the press shown in Figures 1 and 2 the lugs 12 and 13 are disposed substantially in intermediate positions at the ends of the bed 10 and head 11.

The bed 10 is provided with a cylinder 18, within which a plunger 19 reciprocates to move a platen 20 secured thereto. The platen 20 moves upwardly against the head 11 in order to perform a pressing stroke, and is guided in its reciprocation by side plates 21 with beveled portions 22 engaging the correspondingly beveled portions 23 at the corners of the platen 20 (Figure 4). The side plates 21 are secured by the cap screws 24 in recesses in the side members 16. Leakage around the main plunger 19 is prevented by means of a conventional gland construction, generally designated 26. The details of the control mechanism of the press form no part of the present invention, and any desired arrangement may be used. The press shown in Figure 1, for example, is controlled as to its direction of action by the lever 27. A hand wheel 28 also enables the total amount of the pressing force to be varied by the operator in a manner well known to those skilled in the art. In this embodiment of the invention, therefore, as the lugs 12 and 13 pass entirely through the apertures 14 and 15 in the side plates 16, thereby the thrust is applied centrally to the side plates 16 rather than at the edges thereof.

It will be understood that I desire to comprehend within my invention such modifications as come within the scope of the claim and the invention.

Having thus fully described my invention, what I claim as new and desire to secure by Letters Patent is:

A vertical press comprising a press head, a press bed, and side members, said side members

having apertures intermediate the side edges of the side members, said head and bed each being reduced at its sides to provide projections lying adjacent its bottom, and its top, respectively, and vertical side walls above and below said projections, respectively, said projections extending entirely through the respective apertured portions of said side members and adapted to be supported, each by a wall of its respective aperture, and

5 said vertical side walls above and below said projections for the top and bottom, respectively, being entirely in contact with said side members, said head and bed members having portions adjacent said projections bolted to said side members and the bolts being the only securing means for maintaining the head and bed in assembled relation with the side members.

WALTER ERNST.
